MATERIALS MIXER

Raselle Edwards Swarthout, Downey, Calif., assignor to
Challenge-Cook Bros., Incorporated, Los Angeles,
Calif., a corporation of California
Filed Jan. 16, 1961, Ser. No. 82,796
1 Claim. (Cl. 259—152)

This invention relates to a device for mixing materials. Although it is adaptable for use in mixing dry materials, it is particularly adaptable for mixing materials in fluid form, and especially slurry materials such as wet plaster.

In modern building construction, many of the materials which are applied in wet form, such as plaster, are mechanically mixed, in substitution for the old, laborious, and time-consuming hand-mixing operation, and many types of mechanical mixers have been utilized. Most of these mechanical mixers have successfully attained desired time-saving, but many of them are deficient in that a thorough and complete mix is not always accomplished.

Although in the use of some of the rougher slurry materials, full and complete mixing is not necessarily important, in other operations, and particularly in plastering, thorough and complete mixing of the wet plaster is essential if a satisfactory job of plastering is to be obtained.

The device of the present invention readily attains such a complete mechanical mix by providing, by simple mechanical means, extensive multiple flow movements of the materials being mixed in a variety of correlated directions.

It therefore appears that it is an object of the invention to provide a mechanical mixer for slurry materials and for liquids which readily accomplishes a thorough, complete mix in a relatively short period of operation compared with the period of operation of other mixers.

It is another object of the invention to provide such a mechanical mixer which has a minimal number of working parts which permit flow movements of the materials being mixed in a substantial variety of correlated directions.

It is still another object of the invention to provide such a mixer which is simple and inexpensive to construct, assemble, maintain and operate.

With these and other objects in view, the invention consists of the construction, arrangement and combination of the various parts of the device whereby the objects contemplated are attained, as hereinafter set forth, pointed out in the appended claim, and illustrated in the accompanying drawings.

In the drawings:

FIGURE 1 is a side elevational view of a mechanical mixer, partly in section, utilizing the device of the present invention.

FIGURE 2 is an enlarged plan view of the helical mixer blade assembly of the device of the present invention.

FIGURE 3 is a view taken on the line 3—3 of FIGURE 2.

As illustrated in the drawings, a power unit 10 is mounted on a carriage 11, preferably at one end of said carriage 11, and may be enclosed in a housing 12. Said carriage 11 has a bed frame member 13, which may be suitably mounted on a wheel assembly 14. Said carriage 11 has an end frame member 15 supported on and extending upwardly from said bed frame member 13. Said end frame member 15 may also extend downwardly from bed frame member 13 to form a suitable leg support 16. Said carriage 11 also has a second frame member 17 supported on and extending upwardly from said

2

bed frame member 13, intermediate the ends of said bed frame member 13 and externally of said housing 12. A draw bar or shaft 19 may also be mounted on bed frame member 13.

5 A journal box 20 is mounted on said frame member 17, and a horizontally disposed power drive shaft 21, operatively connected to said power unit 10, is supported in said journal box 20. One end 22 of said drive shaft 21 protrudes beyond said journal box 20.

A mixer bin 30 has a body member 31, and end members 32 and 33. Body member 31 has an opening or port 34 for the receipt and discharge of the materials to be mixed. Said bin 30 is axially supported, preferably rotatably, on said journal box 20 at end member 32. The other end member 33 of bin 30 is similarly supported on a journal box 35, said journal box 35 being mounted on end frame member 15. A handle 36 may be mounted on end 33 of bin 30 to aid in rotating bin 30 to discharge position, and a retaining member 37 may be mounted on end frame member 15, and disposed so as to abut on end 33 of bin 30 so as to releasably retain bin 30 in any desired rotated position.

A rotating shaft 40, having ends 41 and 42, is disposed horizontally and axially in said bin 30 between said end members 32 and 33. Said shaft 40 is operatively connected at end 41 thereof to the protruding end 22 of drive shaft 21 by any suitable means, as by a shaft coupling 43. The other end 42 is connected to a spur shaft 44 by any suitable means, as by a second shaft coupling 45, and said spur shaft 44 is supported in journal box 35.

30 A first helical blade 50, having a right-hand helical curvature similar to a right-hand thread, is disposed circumferentially about shaft 40, adjacent end 41 thereof, is spaced apart from said shaft 40, and is supported on shaft 40 by rods 51, 52, 53 and 54. One end 55 of said blade 50 is disposed adjacent to end 32 of bin 30, and the other end 56 of blade 50 is disposed beyond the plane of the longitudinal center of shaft 40.

35 A second helical blade 60, having a left-hand helical curvature similar to a left-hand thread, is also disposed circumferentially about shaft 40, adjacent end 41 thereof, and spaced apart therefrom. Blade 60 is supported on shaft 40 by rods 51 and 53 and by a rod 74. Blade 60 has a diameter smaller than the diameter of blade 50, 40 is disposed within the curvature of said blade 50, is spaced apart therefrom, and is mounted on rods 51 and 53 internally of blade 50. One end 61 of blade 60 is disposed adjacent to end 32 of bin 30, and the other end 62 of blade 60 is disposed beyond the plane of the longitudinal center of shaft 40, preferably in approximate alignment with end 56 of blade 50.

45 A third helical blade 70, having a left-hand helical curvature similar to a left-hand thread, and having a diameter substantially the same as the diameter of blade 50, 50 is disposed circumferentially about shaft 40, adjacent end 42 thereof, is spaced apart from said shaft 40, and is supported on shaft 40 by rods 71, 72, 73 and 74. Blade 70 is mounted on rod 74 externally of blade 60. One end 75 of said blade 70 is disposed adjacent to end 33 55 of bin 30, and the other end 76 of blade 70 is disposed beyond the plane of the longitudinal center of shaft 40.

60 A fourth helical blade 80, having a right-hand helical curvature similar to a right-hand thread, is also disposed circumferentially about shaft 40, adjacent end 42 thereof, and spaced apart therefrom. Blade 80 is supported on shaft 40 by rods 71, 73 and 54. Blade 80 has a diameter substantially the same as the diameter of blade 60, and consequently smaller than the diameter of blade 70, is disposed within the curvature of said blade 70, is spaced 65 apart therefrom, and is mounted on rods 71 and 73 internally of blade 70, and on rod 54 internally of blade 70.

50. One end 81 of said blade 80 is disposed adjacent to end 33 of bin 30, and the other end 82 of blade 80 is disposed beyond the plane of the longitudinal center of shaft 40, preferably in approximate alignment with end 76 of blade 70.

In operation, materials to be mixed are introduced into bin 30 through opening 34. Shaft 40 is then rotated, causing blades 50, 60, 70 and 80 to rotate.

Because of the unique arrangement of the various helical curvatures of blades 50, 60, 70 and 80 relative to each other, and particularly because, instead of the normal one or two helical blades extending throughout the entire longitudinal length of bin 30 found in other mixers, the device of the present invention utilizes two sets of blades, neither of which extends substantially beyond the plane of the horizontal center of shaft 40, a unique mixing action thereupon takes place in bin 30. Right-hand helical curvature blade 50 will cause a mix and flow of the materials toward the center of bin 30, both at the top and bottom of bin 30, where they will be met by flows in the opposite direction caused by left-hand helical curvature blade 70. The meeting and merging of these flows will cause additional mixing not otherwise attained. The flow of materials in the combined mixes will then be directed toward the axial center of bin 30, where the flow will be separated, left-hand helical curvature blade 60 causing a mix and flow of materials axially toward end 32 of bin 30 (where the materials will join the flows in the outer opposite direction caused by rotation of right-hand helical curvature blade 50), with right-hand helical curvature blade 80 causing a mix and flow of materials axially toward end 33 of bin 30 (where the materials will join the flow in the outer opposite direction caused by the rotation of left-hand helical curvature blade 70). This multiple mix and flow of materials in bin 30, and especially the unique mix and flow movement in the center area of bin 30, provides a vastly superior mixing action not otherwise attainable.

When the materials have been thoroughly mixed to the satisfaction of the operator of the device, they may be discharged from bin 30 by grasping handle 35 and rotating bin 30 until opening 34 is in discharge position.

Although the invention has been herein shown and described in what is conceived to be the most practical and preferred embodiment, it is recognized that departures may be made therefrom within the scope of the invention, which is not to be limited to the details disclosed herein but is to be accorded the full scope of the claim

so as to embrace any and all equivalent structures and devices.

Having described my invention, and what I claim as new and desire to secure by Letters Patent is:

5 A materials mixer which comprises: a mixer bin having a first end and a second end; a rotatable shaft disposed axially in said bin between said ends; a first helical blade having a right-hand curvature, disposed circumferentially about and supported by said shaft in spaced 10 relationship thereto, said blade having a first free curving end thereof disposed closely adjacent to the first end of said bin, and having a second free end thereof disposed at a point beyond the plane of the longitudinal center of said shaft; a second helical blade having a left-hand curvature, disposed circumferentially about and supported by said shaft in spaced relationship thereto, said second blade being mounted within the curvature of said first blade, said second blade having a first free curving end thereof disposed closely adjacent to the first end of said 15 bin and overlying the first end of said first blade in spaced relationship thereto, and having a second free end disposed at a point beyond the plane of the longitudinal center of said shaft; a third helical blade having a left-hand curvature, disposed circumferentially about and supported by said shaft in spaced relationship thereto, said third blade having a first free curving end thereof disposed closely adjacent to the second end of said bin, and having a second free end thereof disposed at a point beyond the plane of the longitudinal center of said shaft, said second 20 end overlapping the second end of said first blade in spaced relationship thereto; and a fourth helical blade having a right-hand curvature, disposed circumferentially about and supported by said shaft in spaced relationship thereto, said fourth blade being mounted within the curvature of said third blade, said fourth blade having a first free curving end thereof disposed closely adjacent to the second end of said bin and overlying the first end of said third blade in spaced relationship thereto, and having a second free end disposed at a point beyond the plane of the longitudinal center of said shaft, said second end overlapping the second end of said second blade in spaced 25 relationship thereto.
